BUNDLE BINDING AND TYING MACHINE

James M. Leaver, Jr., Oakland, Calif., assignor of one-half to Donald Parker and Citizens National Trust and Savings Bank of Riverside, administrators

Application May 14, 1924, Serial No. 713,180

71 Claims. (Cl. 100—31)

This invention relates to binding machines and among other objects aims to provide improved bundle clamping mechanism, bundle binding mechanism, binding-band tensioning mechanism, and tying mechanism, as well as an improved combination of these mechanisms in a commercial machine.

This application is also a continuation of invention, in part, of the original and useful 10 bundle binding features disclosed in my co-pending applications, Serial No. 380,375, filed May 10, 1920, and Serial No. 446,942, filed February 21, 1921.

For the purpose of identifying such continuation of invention, with respect to the improvements disclosed in said prior applications, attention is directed to flexing of the wire to provide the wire convexly tensioned while the wire is maintained under tension; the wrapping of 20 the convexly tensioned wire into band formation about the bundle to provide a band thereabout pressing inwardly under its convex tension against three sides of the bundle and in the plane of the wrapping thereof; the arranging of 25 the tie portions of the band substantially parallel to the fourth side of the bundle and in said plane; and the intertwisting of said portions to secure the convexly tensioned band about the bundle.

30 For the purpose of identifying such continuation of invention, with respect to the apparatus features disclosed in said prior applications, attention is directed to the bundle holding means to receive the bundle, as manually placed, in 35 tying location; the movable tension device for preventing slack and maintaining the wire under tension; the tying mechanism fixed in wire receiving location relative to the frame, abutment, and support, and into which tying mechanism 40 the wire is wrapped twice for the binding of each bundle; the means for compensatingly clamping the bundle irrespective of the size of the bundle, within the range of operative movement there- 45 of; the motor and clutch thereof.

45 Other features identifying such continuation of invention, with respect to the apparatus features disclosed in said prior application, will be apparent from the following description, and/or by comparison of the showing of the drawings 50 of this application with the descriptions and/or showing of the drawings of said prior applica- tions.

The invention may be understood by reference to one illustrative embodiment shown in 55 the accompanying drawings, in which:

Figure 1 is a front elevation of the illustrative machine with parts of the frame broken away to reveal the construction;

Fig. 2 is a side elevation, with parts broken away and illustrating machine construction 60 adapted to receive and bind bundles passed end- wise therein directly into binding position;

Fig. 3 is a section on line 3—3 of Fig. 1 showing the gearing which drives the bundle binding mechanism;

Figs. 16 and 17 are diagrammatic views illus- 110

trating the retraction and feeding of the wire, respectively, during the providing of an initial band tie portion in tying register and the formation of the band as the wire is wrapped in an 5 opposite or reverse direction to that shown in Figs. 11 to 15, inclusive;

Fig. 18 is an approximately full size view of the flat wire tie formed by the machine.

The illustrative machine, designed for binding 10 bundles or articles which are moved into binding and tying location in a direction at right angles to the plane in which the wire is banded and tied about the bundle, provides spaced stationary bundle supporting elements; means for holding 15 the bundle on the bundle supporting elements; means for convexly tensioning and passing a band completely around the held bundle in a vertical plane intermediate said spaced stationary bundle supporting elements; and a tying mechanism disposed in said plane which automatically ties the band, commonly a wire. To insure a tightly bound bundle, primary tensioning or feeding means and secondary tensioning or take-up and retracting means are employed which act in conjunction with a wire gripping device to maintain 20 a substantially uniform tension on the wire.

In the operation of the machine, the bundle is clamped; then the wire is passed initially into the tying mechanism and convexly tensioned as 30 it is passed about the bundle and laid against three faces thereof under its convex tension, being finally passed into the tying mechanism, which is slightly spaced from one side of the bundle. During or after formation of the tie, 35 the wire is cut free from the bundle, and the tie, upon completion, is released, whereupon the tied wire closes under its tension against the bundle.

The bundle binding means includes a rotatable member surrounding the bundle support and 40 turning a sufficient distance during each cycle of movement to provide two overlapping strands within the tying mechanism, from which strands the tie is formed. The rotatable member has mounted thereon spaced wire wrapping means 45 which alternately receive and effect the wrapping of the wire, in transfer relation, during the clockwise or counter-clockwise movements of said member.

Associated with the wire cutter is a wire gripping device, which acts to secure the wire end 50 automatically after the wire has been sufficiently intertwined to securely fasten the band about the bundle. The rotatable bundle binding member may be reversed after each binding cycle, to 55 lay the wire again about the same bundle, or about the succeeding bundle, in the opposite direction; and to cooperate with such a member the wire cutting and gripping parts are duplicated on opposite sides of the tying mechanism and are 60 actuated alternately to release the initially secured wire end on one side and to cut the wire free from the bundle and secure the freed end for the succeeding binding operation on the other side.

65 It is to be understood that the illustrative form shown in the drawings is simply a preferred embodiment of the invention; and that in the following explanation of that specific form, the described details of structure and organization are 70 merely exemplary.

Referring first to Figs. 1, 2 and 3, the machine frame 20, which provides the necessary support for the operating mechanisms, is mounted on wheels or casters 21 so that the machine may be 75 moved about. To support the bundle during and

immediately before and after its binding and tying, a roller conveyer is provided consisting of a number of spaced, horizontal rollers 22 journaled in the machine frame and arranged for passage of the bundle through the machine. This roller conveyer exemplifies a convenient form of bundle support which facilitates handling the bundles.

To hold the bundle upon its support during the binding and tying operations, clamping means is provided which in this instance is pneumatically operated. The bundle clamping means shown comprises an arm 23 adjustably secured upon and extending substantially at right angles to an upright reciprocable rod 24 guided by the machine frame, said reciprocable rod, as shown in Fig. 4, entering an air cylinder 25 mounted on a frame. Within the cylinder 25, rod 24 is connected to a piston 26, between which and the lower end of the cylinder is a spring 27, provided to move the piston (and hence clamping arm 23) upwardly when the piston is not subjected to pressure, at which time the clamping arm 23 is a sufficient distance above the bundle support to be out of the way of the bundle. It will be observed from the showing of Figs. 1 and 4, that the bundle clamping means discloses a novel method of effecting the clamping of the bundle, damping the action of the clamp and restoring the bundle clamp to normal position. It will be apparent from the showing of Fig. 4 that the length and tension of the spring 27 determines the control or damping action of the clamp 23, and that any desired damping action may be obtained without recourse to invention, by the use of a spring of desired predetermined length or tension. An air pipe 28 conducts compressed air into the cylinder above the piston when a valve, whose actuation will be described later, is opened, whereupon the piston descends against the pressure of the spring 27 to clamp the bundle. To relieve pressure in the cylinder and thus permit spring 27 to lift the clamping arm 23, an exhaust pipe 29 (Fig. 2) is employed which has a valve 30 opening the pipe to the atmosphere, said valve controlled by means 100 to be described.

After the bundle has been clamped, it is ready for the binding operation, which is accomplished by a rotary band-guiding and laying mechanism which encompasses the bundle with a band, in 105 this instance, a round wire. The illustrative arrangement employs an annular wire-guiding member 31 supported upon an upright extension 32 of the machine frame by several spaced rollers 33 (Fig. 1) which may be grooved to receive an 110 inner annular track 34 provided on the wire-guiding member. As shown, the wire-guiding member completely surrounds the bundle support and extends above the same a sufficient distance to permit the passage of commercial-sized bundles through the machine. Gear teeth 35 are 115 formed on the periphery of the wire-guiding member, to permit driving thereof by power-actuated means, exemplified by the train of gears 36, 37, 38 and 39, gear 36 meshing with teeth 35 of the wire-guiding member and pinion 39 engaging the vertically reciprocable rack 40. It 120 will be observed from the showing of Figs. 1 and 2, that the rotatable gears 36, 37, 38 and 39, and rotatable shafting connected therewith, comprise 125 gearing, or a train of rotatable elements through which the rack 40 transmits movement to, and controls the wire guiding member 31. The rack is guided as at 41 and is operatively 130 connected with a piston rod 42 extending from 135

an air cylinder 43 mounted on the frame. In Fig. 1, it is to be noted that the rotatably mounted gears 36, 37, 38 and 39, step-up the movement of the member 31, when compared with the movement of the rack 40, and/or the piston 42, to provide the necessary distance of rotation of the member 31, and therefore, that said gearing, or train of rotatably mounted gears 36, 37, 38 and 39, constitutes a step-up mechanism for increasing the distance of travel of the member 31, with respect to the distance of travel of the rack 40, and/or the piston 42.

By the described construction, as piston rod 42 is reciprocated (by means to be described) the annular wire guiding member will rotate alternately in opposite directions through more than one revolution in a plane perpendicular to the bundle support to envelop the bundle completely during each cycle of movement of the wire-guiding member. It will be observed that the mechanism for actuating the annular wire guiding member accomplishes the rotation of said member alternately in opposite directions, and the reversal of direction of movement and control thereof, without the employment of gears, frictions, clutches, etc., requiring lateral shifting movement, and/or registering devices. The elimination of such features making for simplified construction and operation, and maximum capacity.

To guide and support the wire 44 during the binding of the bundle, a number of freely rotatable grooved wire guiding wheels 46, 47, 48, 49, 50, 51 and 52 (Fig. 1) are carried upon the annular wire-guiding member. Cooperating with these wheels are two similar, co-adjacently mounted wire-leading or wire-wrapping wheels 53 and 53a, the arrangement of said wheels 53 and 53a being such that the wire leads off from one to the other of said wheels 53 or 53a during the binding, while the extremity of the wire is gripped by means associated, for example, with the tying mechanism, when one is provided. See Fig. 10. When I refer to the "lead" of the wire I have reference to that length of wire extending from the wrapping or "lead" pulleys 53 and 53a to either of the wire gripping means of the bundle and indicated in the drawings, Figs. 1, 8, 10, 11, 15, etc., as 44c. In Figs. 1 and 11 to 17 inclusive, it is to be observed that the two co-adjacently mounted wheels, or sheaves, 53 and 53a, on the ring, provide a lead-off guide instrumentality which is operable on the wire, extending between the gripper and the wire tensioning source, in such manner that the wire is flexed, or convexed, away from the bundle in the plane of movement of the wire while the wire is maintained under tension, thereby causing the wire, when applied to the bundle, to press inwardly and tightly under its convex tension against the sides of the bundle when wrapped thereabout.

The aforesaid described arrangement of the wheels, or sheaves, 53 and 53a, follows the teachings and disclosure of my co-pending application Serial No. 446,942, filed February 21, 1921, wherein like wheels, or sheaves, 94 and 95, and 95a, (Figs. 1, 2 and 9,) are co-adjacently mounted and operable in a similar manner and for the purpose set forth herein with respect to the sheaves 53 and 53a. In the machine of this application, I have substituted the ring shaped carrier 31, such as shown in the patent to S. T. Holly, No. 65,746, issued June 11, 1867, for the carrier 38 shown in my co-pending application, Serial No. 446,942, and have mounted on said ring carrier, the

sheaves 53 and 53a, in respective wire guiding positions corresponding to the respective wire guiding positions of the sheaves 94, 95, and 95a, (Figs. 1 and 9 of said co-pending application Serial No. 446,942) whereby the wire is convexly curved toward the axis of the bundle in a given plane during a reversal of direction of movement of the wire to provide the wire so convexly tensioned as to effect tight hugging of the wire about the bundle, such disclosure exemplifying my new and useful improvements for wrapping the wire for more than the perimeter of the bundle and twice into tying location for overlapping in said plane, with the wire convexed to press inwardly and tightly against the three sides of the bundle during the wrapping movement of the wire about the bundle.

The operation of binding a bundle is illustrated diagrammatically in Figs. 11-17 inclusive, Figs. 12, 13, 14 and 15 showing positions of the parts during and at the completion of clockwise rotation, and Figs. 16 and 17 two positions during counter-clockwise rotation, Fig. 11 being a diagram of the parts when at rest, corresponding to Fig. 1. When the wire-guiding member turns in either direction, the wire passes through an opening 54 (Fig. 3) in the machine frame to engage the horizontal face of the bundle. The described bundle binding mechanism lays a wire or other band completely around a bundle without the aid of wire clamps or wire-holding means, and guides and wraps the wire successively and accurately into the tying mechanism during each bundle binding operation to provide overlapping portions of the band for the formation of the tie. The wrapping is so accomplished, however, that the wire is not drawn longitudinally across a face of the bundle, which might disfigure it.

During certain phases of the bundle-binding cycle, the wire is drawn through offset tensioning means from its source of supply, while during other phases the wire is not so drawn but is at times retracted by the adjustable tensioning means (55) to provide the binding of the bundle under proper tension at all times during the clockwise and counterclockwise movements of the wrapping means, as will be apparent from a comparison of Fig. 1 and Figs. 11 and 13 or Figs. 11 and 16. Thus to maintain a tension on the wire at all times, the machine has a positively acting mechanism for taking up slack which cooperates with a wire-braking or wire-feed-checking mechanism, both mechanisms being interposed between the wire supplying means (not shown) and the bundle binding member already described.

The slack-take-up or secondary tensioning device is shown in Figs. 1 and 5 as comprising a bar 55 mounted to reciprocate vertically in the plane of the wire guiding wheels provided on the annular member 31 and having a removable weight 56 on its lower end, said weight slidable on an upright rod 57 fast to the machine frame. At the upper end of reciprocable bar 55 a wire-guiding wheel 58 is provided for engaging the wire 44a from the wire-feed-checking device 59, (Fig. 1). As the wire slackens, the slack-take-up device will descend to retract the surplus wire and thus maintain the wire under tension; but as more wire is drawn out during the binding process, with consequent pull upon the wire, the slack-take-up device rises or tends to rise on its guiding rod, whereupon the wire is fed to the annular bundle-binding member. Cushioning means for the slack-take-up device is shown in 150

the form of a coil spring 60 (Fig. 5), which will prevent striking of the weighted end of bar 55 against the machine frame at the upper end of rod 57, and will, when compressed, increase the 5 pull of the slack-take-up device on the wire. The spring also accelerates the initial action of the slack-take-up device when the bundle-binding means reverses. Obviously, this pull may be regulated, for instance by using weights of different 10 masses. When I refer to "retraction" or "slack-take-up" of the wire I have reference to the withdrawal or retraction of a portion of the wire 44b, Figs. 11, 12 and 13, during the reversal of movement of the wire binding means 31, 53 and 15 53a, whereby in such withdrawal or retraction of the wire adjustable working control and tension of the wire is effected.

The wire-feed-checking or primary tensioning device 59 shown comprises a series of staggered 20 rollers 59a mounted on a carrier secured to the frame extension 32, some of the rollers being adjustable to regulate the bend in the wire, which is trained between the rollers. By varying the bend of the wire it is braked as desired. Associated with the device 59 is a wire guiding and straightening tube, or device, 59b which guides the wire supply strand 44 into alignment with the grooves of the staggered feed-checking or tensioning rollers 59a and which tube, or device, 25 59b also removes kinks and twists from the supply wire 44 as the latter is drawn therethrough. From the feed-checking device or origin of tensioning the wire passes to wheel 58 of the slack-take-up device, thence between wire-guiding 30 wheels 60a on the frame extension 32, and to 35 the wheels 46—53.

The mechanism described above exemplifies automatic bundle binding means which rotates alternately in opposite directions to envelop a bundle with a tensioned wire band during each cycle 40 of movement in either direction, the tension on the wire being maintained substantially uniform whatever the size or shape of the bundle.

To secure the wire to the bundle, it may be tied 45 or secured by hand; or an automatic tying mechanism may be provided. The tying mechanism shown is claimed herein only in combination with certain parts of the machine; however, it is illustrated sufficiently for a comprehension of the operation thereof in Figs. 8, 9 and 10, while the operating mechanism therefor is best shown in Fig. 50 2. By reference to Figs. 9 and 11 to 15, inclusive, it is seen that the tying mechanism of this machine is located within the path of movement of 55 the wire guided by the means, 53 and 53a, so as to provide for the passing of each portion, or strand, of the wire required for the tie to secure the band about the bundle, directly into the tying mechanism and in overlapping relation therein in 60 the plane in which the wire is wrapped about the bundle.

The aforesaid described principle of wrapping each tie portion, or strand, of the wire required 65 for the tie, into the tying mechanism follows the teachings and disclosure of my co-pending application, Serial No. 446,942, filed February 21, 1921. In the machine of this application, I have substituted a flat tie, or flat joint, tying mechanism 70 similar to the tying mechanism disclosed in the patent to A. Heim, No. 1,031,444, filed July 2, 1912, in respect to the tying of a flat knot, or flat joint, in such manner that the same is discharged toward the bundle; the bearing for the tying feature having a diametrical slot therethrough pro-

viding for the normal position of the tying feature being in register with said slot to receive each tie portion of the banded wire through said slot directly from the binding means, and after the formation of the tie, said tying feature being in another position of register with the slot for discharging the tie therethrough toward the bundle. In my machine, I have improved upon the tying mechanism and principle disclosed in the Heim patent, by providing for the tying of small bundles, in the manner hereinafter described.

From the aforesaid description, it will be obvious that I have continued invention relative to the principles and improvements disclosed in my co-pending applications, Serial No. 380,375 and Serial No. 446,942, for the purpose of adapting the same to the forming a flat tie, or flat joint, dischargeable toward the bundle.

When I refer to "wire strands", "tie portions", "tie strands", "overlapping strands", "to overlap the wire", or terms of similar expression, I have reference to those portions, or bights, of the strand *j*, designated as 44d and 44e. Figs. 12 to 17, inclusive, and 9 and 18, of the drawings, disclose the manner in which dual portions, or bights, 44d 95 and 44e, are wrapped and provided directly into overlapping tying register during the wrapping of the wire to effect the binding of the bundle.

Secured to the machine frame are two brackets or frames 61, 62 which together support the tying 105 mechanism and provide an upright abutment against which one face of the bundle may be thrust before binding (Fig. 1), to position the bundle properly relative to the parts which form the tie. These frames are spaced slightly apart, 110 as shown in Fig. 8 to provide a passageway 63 through which the wire is guided into the twister by the surrounding annular guiding member and through which the wire, after being twisted, passes to the bundle. Clearly, the passageway 63 115 extends substantially in the plane of the wire guiding wheels 46, 47, etc.

Upon frame 62, adjacent passageway 63, and arranged respectively above and below the wire twister shell or barrel 64, are two swingable cutters 65 and 66 respectively, each of which is in the form of an arcuate plate carrying a wire severing knife. The upper cutter 65 is shown on an enlarged scale in Fig. 10. The two cutters are 120 exactly alike in construction and in function but 125 cut the wire alternately on opposite sides of the twister.

As shown in Fig. 8, the two cutters 65, 66 are oppositely pivoted as at 67 and 68 respectively, to be swingable across the wire passageway 63. 130 The mechanism shown for swinging the cutters alternately includes the eccentric arms 69, 70 pivotally connected to the cutters at one end and having their eccentrics mounted on shafts 71, 72 supported on frame 62. Shaft 72 is rotated by 135 bevel gears 73, 74, the latter fast to shaft 75 having a bevel gear 76 at its lower end (Fig. 2) meshing with a similar gear 77 supported by a shaft 78. Shaft 71 is driven synchronously with shaft 72 by the meshing gears 79, 80 secured to the respective shafts.

The selected mechanism for intermittently actuating the cutters, as shown in Figs. 2 and 7, comprises a power-reciprocated bar 81, herein a rack, slidable through fixed guides 82 and pivotally connected to a bar 83 whose opposite end is supported as at 84. Arranged at regular intervals on the back of bevel gear 77 are projecting rollers 85 (Figs. 1 and 2) successively engaged by a lug 86 on bar 83 during the left-to- 140 right movement of bar 81.

right strokes of said bar, as viewed in Fig. 2; the lug 86 having an inclined face 87 enabling it to ride over the rollers 85 upon the return stroke of bar 83. The opposite end of rack 81 enters a cylinder 88 mounted upon the machine frame and is connected with a piston (not shown) for reciprocation. The mechanism disclosed exemplifies means intermittently effecting alternate cutting of the wire on opposite sides of the tie-forming member.

Referring to Fig. 10, the upper cutter 65 (which is structurally and functionally identical with the lower cutter 66), has its arcuate edge 89 mating with a shear plate 90 affixed to frame 62, one end 15 of the shear plate terminating at passageway 63 and providing a shearing edge 91 cooperating with a knife 92 on the cutter. The knife 92 is provided by a projection integral with the arcuate cutter 65 and extending toward the frame, the 20 upper face 93 of said knife serving as one part of the wire-end gripping means. It will be clear that when the cutter is swung across passageway 63 in the direction of its supporting frame the knife will engage the strand of wire extending in 25 said passageway and shear it. By reference to Fig. 10, it will be seen that an anvil 94 projects beyond the cutting edge of the shear plate 90, thus providing for the bending of the wire there-over by the upper inner edge of the knife 92 before the severing of the wire takes place, thus insuring a bend or kink in the wire sufficient to 30 securely hold the same for the following binding operation and before the cutting of the wire. As shown, the anvil 94 has a rounded edge to 35 prevent any cutting of the wire by the upper edge of knife 92 during the bending or kinking of the wire. The upper edge of the knife 92 is shown as angular for the purpose of forming an acute kink, or bend, in the wire before the cutting of the wire takes place. From the disclosure of 40 Fig. 8, it will be readily understood that the timing or normal position of the gripping and cutting means 92 may be readily modified by simply so arranging the meshing of gears as to provide 45 the desired adjustment of the same through the medium of the eccentrics, which operate the eccentric arms 69 and 70.

When the wire is cut, its free end continues to bend about the anvil 94 provided by the end edge 50 of head 95 of a gripper arm 96 pivoted to the frame 62 as at 97 (Fig. 8) to swing between the arcuate plate and the frame. The lower edge of head 95 is spaced a sufficient distance from the upper face 93 of the knife to permit the bent wire 55 end to pass into said space and be gripped between the head 95 and said knife. Thus the knife and gripper arm cooperate to secure the wire preliminary to the cutting thereof, in readiness for the succeeding bundle binding operation.

At an intermediate point on gripper arm 96 a pin 98 is pivotally connected and is slidable through frame 62, said pin being adjusted longitudinally by a nut 99 at its upper end. A coil spring 100 carried by the pin presses the head 95 of the gripper arm against the knife. By turning the nut 99 the wire-end gripping parts are adjusted to accommodate wire of different gages; and at the same time tension of spring 100 is varied. The described construction permits swinging of the gripper arm under certain conditions, but insures a tight hold on the bent wire end during operation of the machine. The binding member 31 of this application, in like manner to the binding member 38 of my parent

co-pending application Serial No. 446,942 filed Feb. 21, 1921, has two positions of reversal relative to the knotter mechanism and to its reversing movement causes the overlapping of parallel strands within the slot of the knotter for the forming of a tie therein; and said binding member also moves a sufficient distance during each cycle of operation to wrap a wire progressively about the successive faces of a bundle in addition to overlapping the parallel tie strands as aforesaid.

In view of the foregoing description of this invention it will be readily seen that the wire binding member 31, of this invention, in like manner to the binding member 38 of my parent co-pending application Serial No. 446,942, filed February 21, 1921, has a rotary or revoluble motion about a stationary bundle and positions tie strands of wire in overlapping relation (Fig. 15) within the knotting mechanism without the aid of auxiliary devices, and the means employed for delivering or guiding the binding wire in tensioned and operative state to the binding member 31 of this application are similar to the means employed in said co-pending parent application 100 for accomplishing said results.

When the bundle has been bound, the wire strands overlap adjacent the wire-end gripper, because of the described movement of the bundle binding member through more than one revolution. The strands are united by the wire twister 64 shown as a longitudinally slotted tube having at an intermediate point a slotted pinion 101 (Fig. 9). The slot 101a (Fig. 9) in the twister pinion 101 is narrower than the slot 64a in both 110 ends of the twister so that the overlapping portions of the wire, or overlapping wire strands, 44d and 44e, are held substantially parallel by the narrow slot 101a while the twisting of the extended overlapping portions of the wire is performed within the barrel or larger slot, 64a, and at both sides of the slot 101a, and is supported for axial rotation between frames 61, 62, so that its longitudinal slot in one position thereof may extend in the passageway 63, first to receive the wire 120 from the bundle binding parts, and after twisting thereof, to discharge the tied wire in the direction of the bundle, towards which it will move owing to its tension. The twister shown is so constructed and arranged that it will not be 125 clogged by sawdust, chips, dirt and loose ends of wire.

The twister operating means shown comprises a gear 102 (Fig. 8) meshing with the twister pinion 101, said gear secured upon a shaft 104 130 journaled in frame 61. The lower end of said shaft carries a pinion 105 (Figs. 1 and 7) which is rotated alternately in opposite directions by rack 81, so that the twister itself is similarly rotated.

During the twisting of the wires they are prevented from prematurely springing out of the slotted twister in direction of the bundle by a pair of retaining members 150 slidably mounted on frame 61 (Fig. 8), which extend between the 140 wire and the bundle at both ends of the twister. These retaining members 150 are held projected across the passageway 63 by springs 151, and are moved out of that position by arms 152 on the shaft 104, which engage lugs 153 projecting from 145 the side of the fingers at the completion of each twisting operation.

By reference to Figs. 1 and 9, it will be noted that the retaining fingers 150 particularly provide for the binding of small packages, inasmuch 150

as said fingers are arranged adjacent each end of the twister 101 in such manner that the wire strands inclined toward the bundle, and required for intertwisting to form the tie, are held free from contact with the shell 64 of the twister, during the formation of the tie, irrespective of the size of the bundle.

It will be noted from Fig. 8 that said retaining fingers 150 are so actuated in timed relation 10 with the operation of the twister that upon completion of the tie said fingers are reeded to permit the discharge of the wire and the formed tie through the passageway 63, toward and against the near face of the bundle.

15 In view of the aforesaid description, and the showing of the drawings, with respect to the wire retaining features, it will be seen that my invention introduces new and novel features of aligning the wire to provide for the intertwisting 20 thereof irrespective of the size of the bundle, and thereafter the unobstructed discharge of the wire and tie through a passageway, toward the bundle, said passageway being in a plane in which the binding means wraps the wire about 25 the bundle and into the twisting means.

It will be observed from the showing of Fig. 9 that the fingers 150 also serve the purpose of registering the wire with the bore 64a of the twister 101, in such manner as to provide for the 30 formation of a flat knot, or flat tie, (see Fig. 18) during the rotation of the twister.

35 When I use the term "flat joint", "flat knot", or "flat tie", or "substantially flat tie", "substantially flat knot", or "substantially flat joint", I have reference to that type of joint, knot, or intertwined tie which is formed of longitudinally passing strands arranged in substantial parallelism intermediate the longitudinal edges of a side of the bundle, and which joint, knot, or tie 40 is formed parallel to and will lie flat against said side of the bundle when released under the tension of the encircled band.

45 The air cylinder 43 (Fig. 1) is connected with a source of air pressure (not shown) and may be employed as a primary actuating cylinder for the machine. To supply compressed air intermittently to cylinder 25, pipe 28 is connected with a valve chest 110 of cylinder 43, Fig. 1, the arrangement preferably being such that the compressed air is admitted to cylinder 25 (effecting 50 clamping of the bundle) just as the bundle binding mechanism starts. As shown in Fig. 2, rack 81 carries a pawl 111 which in each left-to-right stroke of the rack, as viewed in that figure engages a control arm 112 of valve 30 to open cylinder 25 to the atmosphere, thus effecting release of the bundle by the clamping arm 23. Valve 30 is closed automatically, for instance 55 by a spring (not shown).

60 Referring to Figs. 1 and 2, the piston in cylinder 25, which reciprocates rack 81, is governed by a two-way valve 113 which controls the flow of air through pipes 114 leading to opposite ends of cylinder 25. Valve 113 is connected by pipes 65 115, 116 with the cylinder 43 so that cylinder 25 is always under pressure.

65 The controlling mechanism for the different valves is shown best in Figs. 1, 2 and 6. An operating lever in the form of a bi-pedal 117 is pivoted as at 118 upon the machine frame and is normally equalized by opposed springs 119 on the frame-supported rod 120, said springs bearing against the pedal arm 121. The pedal 117 is connected by links 122 and 123 (Figs. 1 and 2) 70 with a rock shaft 124 supported upon the ma-

chine frame as best shown in Fig. 2. At the other end of the rock shaft 124 a lever 125 is secured, the normal position of said lever being as shown in Fig. 1. To rock shaft 124, intermediate the link 123 and lever 125 a slotted link 82 85 126 (Fig. 1) is secured, and as shown has a pin-and-slot connection with the slideable valve-control rod 127 which governs the piston in cylinder 43. Thus, when the pedal 117 is depressed at either end, the bundle binding mechanism is actuated in one direction or the other.

90 Supported on the machine frame above rod 120 is a rock shaft 128 having at one end a lever 129 (Figs. 2 and 6) to which is pivotally connected a vertical spring-lifted rod 130. The rod lifting spring 131 may be placed, as shown, between the machine frame and the upper enlarged head 132 of rod 130. The pedal arm 121 carries a flat spring 133, which in the intermediate position of the pedal engages a detent 95 134 on rock shaft 128, thus preventing said rock shaft being rocked by spring 131. But when the pedal is depressed at either end, the flat spring 133 will move out of contact with detent 134, permitting the rod 130 to move upwardly.

100 By means of a slotted arm 135, (Fig. 1) whose slot receives a pin on rod 130, a rock shaft 136 carried on the machine frame is connected with rock shaft 128. An arm 137 at the opposite end of rock shaft 136 is pivotally connected with a valve control rod 138 having a lug 139 (Fig. 1) 105 designed to engage the control arm 140 of valve 113, which as described actuates the tying mechanism through rack 81. Valve 113 is moved automatically by a spring (not shown) to admit 110 air to the opposite end of cylinder 25 when lug 139 is moved out of engagement with control arm 140. The control rod 138 passes through guides 141 provided on the underside of lever 125 so that when rock shaft 124 is rocked, the 115 control rod 138 likewise is rocked, thus separating lug 139 from valve control arm 140. To rock shaft 136 there is also secured an arm 142 (Fig. 1) having a pin-and-slot connection with a vertical rod 143 projecting through the machine 120 frame alongside rack 40. This rack at its lower end has an extension 144 which receives the vertical rod 143, so that when the rack 40 approaches its upper limit of travel, its extension 144 will engage head 145 of vertical rod 143, 125 thereby to move said rod upwardly against the tension of the spring 131 and oscillate rock shaft 136, with consequent actuation of valve control rod 138.

130 The operation of the machine is briefly as follows: After a bundle or other object to be bound is placed on the roller conveyer, the operator depresses the right hand end of operating pedal 117 (as viewed in Fig. 1), which causes rocking of lever 125 and hence tilting of valve control 135 rod 138 out of engagement with valve arm 140, whereupon the valve 113 is moved by its spring to admit compressed air into one end of cylinder 25. The rack 81 then moves to the left as seen in Fig. 2 and rotates the twister 101, which stops 140 with its slot registering with the passageway 63, as in Fig. 9, in position to receive the incoming wire strands from the surrounding binding mechanism. During this initial movement of rack 81 the wire gripping and cutting parts are 145 stationary.

150 Simultaneously with the aforesaid depression of the operating pedal, the valve control rod 127 is moved downwardly, permitting compressed air to pass through pipe 28 to cylinder 25. The 150

bundle is then clamped. This movement of the valve control rod 127 admits compressed air to one end of cylinder 43, causing the rack 40 to move upwardly to rotate the bundle binding mechanism through more than one revolution, thus passing the wire completely around the bundle and laying the wire against three faces of the bundle (Figs. 11-14), and finally overlapping the wire in the slotted twister, at the 5 fourth face of the bundle as shown in Figs. 9 and 15. It will be apparent from the aforesaid description, and Figs. 1 and 2, that this invention embraces novel construction and operative features providing for simultaneous actuation 10 of the bundle-binding member and the clamping means. Such novel operation of the binding member and the clamp, of this application, is of primary importance in that it eliminates the objectionable feature of intervals of time between the binding and clamping operations, so 15 prevalent in the prior art, and makes for simplicity of construction and operation and increased capacity.

When the bundle envelopment is being completed, the rack extension 144 lifts rod 143, from the position in which the tension spring 131 will adjust the rod 143 through the means 130, 132, 135, 136, and 137, when the extension 144 is not in contact with the head 145 of said rod 143, to 20 oscillate rock shaft 136 and cause projection of valve control rod 138, whose lug 139 engages valve arm 140 as shown in Fig. 1 and moves valve 113 into a position which admits air into the opposite end of cylinder 88, thereby moving rack 81 to the 25 right as viewed in Fig. 2. During this movement of said rack, the shaft 104 is rotated to effect twisting of the overlapped wire strands to form the tie, Fig. 18. The same motion of rack 81 also opens valve 30, thus effecting release of the bundle. After the overlapped tie portions, or strands, 30 of the wire have been securely intertwined, so that the possibility of slipping of the twisted wires is eliminated, the initially secured end 44c of the wire is released by the wire gripping parts, and the bend in 44c is partially straightened out by 35 the slight further action of the twister to the final form shown in Fig. 18. At about the same time, the cutter at the opposite end of the twister is actuated to form a holding bend in the wire 40 against the anvil 94 and cut the wire between the tie and the bend, and immediately after cutting to additionally secure the wire end so formed for the succeeding bundle binding cycle. With the 45 completion of the tie, the twister 101 stops in a position diametrically opposite to that of Fig. 9, to discharge the tied wire in the direction of the bundle. The tension of the wire then causes it to close tightly against the side of the bundle. Thus the cycle is completed.

From the foregoing description, it will be apparent that the actuation of the twisting means takes place quickly upon completion of the binding of the bundle, by reason of the extension 144, mounted on the actuating member 40, effecting movement of the rod 143 simultaneously with the completion of the binding of the bundle, whereby the twister actuating means becomes active quickly and substantially at the point of completion of the binding movement of said member.

Inasmuch as the present disclosure shows fluid-actuated means for effecting actuation of the twister, it will be apparent that the primary object of the invention is to effect the tying of the wire at the earliest possible moment upon the completion of the binding of the bundle, and it is

believed, from the operation and structure of the features 130 to 144, inclusive, it will be apparent that it requires no invention to change the length, or leverages, or degree of movement of such features so as to modify the timing of the actuation of the twister with respect to quickly actuating the twister either simultaneously upon completion of the binding movement, or substantially at the point of said completion of the binding movement.

To initiate the succeeding cycle, the opposite or left end of bi-pedal 117 is depressed, causing the same operations as before, the only difference being that valve control rod 127 is moved oppositely, causing descent of rack 40 at the start and rotation of the annular bundle binding member in the opposite direction. Irrespective of the movement of the bundle binding member, the wire is constantly tensioned by the yielding and retracting slack-take-up device 55 working in conjunction with the wire-feed-checking or primary tension device 59.

The wire tying parts are so constructed and arranged that the initial elongation and torsion of the wire, during formation of the tie, are in 100 part transmitted to the wire passing around the bundle. For the purpose of exemplifying the principle of forming a tie with the twisting requirements of the wire, necessary to form the tie, primarily provided from the wire passing around 105 the bundle, Fig. 9, shows one portion of the wire i. e., the initially secured end; rigidly held; the wire laid in the twister after bundle envelopment is thus free to move longitudinally or axially, if subjected to sufficient tension or torsion. In 110 short, the tie is substantially a "free running" tie, the twisted part being free to creep to a certain extent, if the wire is stressed excessively. Hence excessive elongation and torsion of the wire, causing weakening or even breaking thereof, is prevented. The fluid actuated machine of the drawings, has been included in this application, preferably for the reason that fluid pressure actuating means and valves for operating the same, are of such well known construction that 115 it requires but limited description to explain and recite the operation thereof. Fluid pressure means, valves for actuating the same and mechanism for actuating the valves, are disclosed in the prior art in patents No. 1,324,238, No. 1,324,239, and No. 1,324,039, issued to C. E. Evans, December 9, 1919, and which patents are now owned by me.

Referring to my patents for Bundle binding machines, No. 1,260,003, issued March 19, 1918, 130 and No. 1,295,531, issued February 25, 1919, and patent to N. B. Thompson, No. 1,152,670, issued September 7, 1915, owned by me, it will be understood that the substitution of mechanical means, in place of a fluid pressure means of this machine, for actuating the clamp, binding means, and tying, gripping, cutting and retaining means, are well known to me and within my extensive knowledge and experience and skill with respect to the construction of bundle binding and tying 140 machines. Upon the issuance of my co-pending applications Serial No. 380,375, filed May 10, 1920, and Serial No. 446,942, filed February 21, 1921, as United States Letters Patents, such consideration of substitution will be further obvious to 145 those skilled in the art.

Obviously the present invention is not restricted either to the particular embodiment thereof herein shown and described, or to the particular principle herein disclosed. Neither is it neces- 150

sary that all the features of the invention be used conjointly; they may be employed advantageously in various combinations and sub-combinations as defined in the claims.

5. What I claim is:

1. A machine of the class described comprising, in combination, mechanism surrounding the object to be bound for guiding and laying a band completely around said object during each cycle

10 of movement in one direction; and means actuating said mechanism alternately in opposite directions to effect binding of the objects alternately in opposite directions; said actuating means consisting solely of members fixed against lateral shifting movement.

15 2. A machine of the class described comprising, in combination, a bundle support; an annular bundle-binding member surrounding the bundle support; and driving means for said member rotating it alternately in opposite directions to effect binding of the bundle, at spaced intervals, alternately in opposite directions; said means consisting solely of members fixed against lateral shifting movement.

20 3. A machine of the class described comprising, in combination, a bundle support; an annular bundle-binding member surrounding the bundle support; and means for effecting simultaneous actuation of the clamping means and the bundle

25 binding means and for rotating said bundle binding member alternately in opposite directions with an interval of rest; and a wire tying mechanism operable during each interval of rest to unite the wire strands.

30 35 4. A machine of the class described comprising, in combination, mechanism for binding an object with a strand of wire; means for driving said mechanism consisting solely of members fixed against lateral shifting movement; said means driving said mechanism alternately in opposite directions to effect binding of the objects alternately in opposite directions; and wire tying mechanism positioned within the path of travel of the wire to unite the wire in a flat tie

45 at the completion of each binding operation.

50 5. A machine of the class described comprising, in combination, a bundle support; a bundle-binding member movable in opposite directions about the bundle support; wire tying mechanism fixed relative to the bundle support; means for clamping a bundle on the support; means for simultaneously actuating said bundle-binding member and said clamping means; the bundle binding member being constructed and arranged

55 to place a wire completely around the bundle in each movement in either direction and to overlap the wire within the tying mechanism; and means for maintaining the wire taut during movement of the bundle-binding member in opposite directions.

60 6. A machine of the class described comprising, in combination, a bundle-binding member; wire tying mechanism; the bundle binding member being constructed and arranged to place a wire completely around a bundle and to overlap the wire in a vertical plane within the tying mechanism; and driving means for the bundle binding member comprising a driving member fixed against lateral shifting movement and movable in opposite directions, and connections interposed between said member of the driving means and the bundle-binding member for effecting movement of the bundle-binding member in opposite directions.

65 7. A machine of the class described comprising,

ing, in combination, a rotary bundle-binding member; wire tying mechanism for forming a flat tie; the bundle binding member being constructed and arranged to place a wire completely around a bundle and to overlap the wire in a vertical plane within the tying mechanism; and means to rotate the bundle binding member alternately in opposite directions; said means to rotate the bundle-binding member comprising a driving member fixed against lateral shifting movement and movable alternately in opposite directions, and connections interposed between the driving member and the bundle-binding member.

8. A machine of the class described comprising, in combination, means for securing one end of a wire; a rotary bundle-binding member fixed against lateral shifting movement and constructed and arranged to lay the wire, whose end is held, completely around a bundle in a vertical plane, successively in contact with three faces thereof and to overlap the extremities of the wire in said plane at the fourth face of the bundle; means to unite said overlapped extremities into a flat tie comprising a rotary slotted twister; means including a source of power for actuating the machine in a cycle; and means for actuating the bundle-binding member directly said cycle begins.

9. A machine of the class described comprising, in combination, a rotary bundle-binding member constructed and arranged to lay a wire strand completely around a bundle to provide overlapping strands for forming a flat tie; driving means for the member comprising a reversing gear, reversible driving connections interposed between said reversing gear and the bundle-binding member, and a toothed driving element fixed against lateral shifting movement and operable in opposite directions in mesh with said reversing gear for effecting rotation of the bundle-binding member in opposite directions, with an interval of rest, through said connections; and means positioned within the path of travel of the wire to receive and unite the overlapping extremities of the wire into the flat tie during said interval of rest.

10. A machine of the class described comprising, in combination, a bundle support; means for clamping a bundle on the support; a twister fixed relative to the support; a bundle-binding member constructed and arranged to lay the wire completely around a bundle successively in contact with three faces thereof and to overlap the wire within the twister at the fourth face of the bundle, said bundle-binding member overlapping the strands in said twister without the aid of clamping means; and means for effecting simultaneous actuation of the clamping means and the bundle-binding member.

11. A machine of the class described comprising, in combination, wire feed controlling means; wire takeup means; mechanism for guiding and laying a band completely about a bundle in one cycle of movement; means for tying the band so laid; and driving means comprising a rack and pinion effecting reversal of the band-guiding and laying mechanism to enclose a second bundle with a band in the opposite cycle of movement.

12. A machine of the class described comprising, in combination, a bundle support; a bundle positioning abutment fixed relative to the support; means for gripping the end of a wire; means for feeding the wire at predetermined tension for binding a bundle positioned on the

- support; means active on the wire intermediate of the gripped end and the feeding means to maintain the length of wire therebetween free of slack; wire tying mechanism including a rotary slotted twister; an annular bundle binding member encircling the abutment and said tying mechanism and revoluble about a bundle positioned on the support to carry the wire therearound in a plane aligned with the slot in said twister; and driving means for the bundle-binding member consisting solely of members fixed against lateral shifting movement, said members comprising a pinion gear, step-up gearing interposed between the pinion gear and the bundle-binding member, and a toothed element constantly meshing with said pinion gear; said wire entering the slot of the twister and successively enveloping the faces of the bundle and again entering the slot of the twister to overlie the initially positioned wire, through the actuation of said member. 10 80
13. A machine of the class described comprising, in combination, a bundle support; a bundle positioning abutment; wire tying mechanism including a rotary slotted twister adjacent said abutment; an annular bundle binding means encircling said support, said abutment and said tying mechanism, and constructed and arranged to revolve about a bundle positioned on the support to lay a wire therearound in a plane aligned with the slot of the twister; and driving means for the bundle-binding member consisting solely of members fixed against lateral shifting movement, said members comprising a rotatable shaft, a pinion gear secured to said shaft, step-up gearing interposed between the pinion gear and the bundle-binding member, and a toothed element permanently meshing with said pinion gear; said wire entering the slot of the twister, then successively enveloping the faces of the bundle, and again entering the slot of the twister to overlie the initially positioned wire through actuation of said member. 25 90
14. A machine of the class described comprising, in combination, a bundle support; means for holding a bundle on the support; wire tying mechanism including a rotary slotted twister; bundle binding means revoluble about the bundle to carry a wire therearound in a plane aligned with the slot in said twister; said wire entering the slot of the twister, then enveloping the successive faces of the bundle, and again entering into the slot of the twister to overlie the initially positioned wire through actuation of said member; and means for effecting simultaneous actuation of the clamping means and the bundle-binding means. 30 95
15. A machine of the class described comprising, in combination, a main frame; a conveyer supported upon the frame and providing a bundle support; an auxiliary frame at one side of the conveyer providing a bundle-positioning abutment; spaced wire tie section retaining means slidably mounted on the abutment; tying mechanism carried by the auxiliary frame comprising a slotted rotary twister positioned intermediate of said retaining means; and bundle binding means operating at right angles to the bundle support and carried by the main frame. 35 100
16. A machine of the class described comprising, in combination, a frame; a horizontal roller conveyer carried upon the frame to support the bundles; fluid-actuated means to clamp the bundles on the conveyer support; bundle binding means operable in a vertical plane at right angles 40 105
- to the direction of movement of bundles along the roller conveyer; a slotted rotary twister having its slot facing in said plane for receiving wire from the binding means; and plural wire feed restraining instrumentalities on the frame successively operable on a strand of wire for maintaining the wire under desired working and binding tension. 45 110
17. A machine of the class described comprising, in combination, a frame, a horizontal conveyer carried upon the frame to support the bundles; fluid actuated means to clamp the bundles on the conveyer support; rotary annular bundle binding means surrounding the conveyer and operable in a vertical plane, at right angles to the direction of movement of bundles along the conveyer; a slotted twister having its slot facing in said plane for receiving wire from the binding means; and plural wire feed restraining instrumentalities on the frame constructed and arranged to successively operate on a strand of wire for maintaining the wire under desired working and binding tension. 50 115
18. A machine of the class described comprising, in combination, a frame; a fixed horizontal bundle supporting conveyer carried by the frame; an upright combined bundle-positioning abutment and tying mechanism support fixed to the frame and extending in the direction of movement of bundles along the conveyer; bundle binding means operable in a plane at right angles to said direction of movement; and tying mechanism including a slotted rotary twister having its slot facing in said plane for receiving wire from the binding means. 55 120
19. A machine of the class described comprising, in combination, a main frame; a horizontal bundle supporting conveyer carried by the frame; an auxiliary frame providing an upright bundle-positioning face extending in the direction of movement of bundles along the conveyer; a tying mechanism carried upon the auxiliary frame out of the path of said bundles; and bundle binding means operable in a vertical plane at right angles to said direction of movement. 60 125
20. A machine of the class described comprising, in combination, a bundle support; wire feed controlling means; wire takeup means; rotary bundle-binding mechanism; and means rotating said mechanism through more than one revolution in each cycle to encompass a bundle with wire in a vertical plane and to provide longitudinally overlapping strands of the wire in said plane for the formation of a flat tie; said means for rotating said mechanism consisting solely of members fixed against lateral shifting movement. 65 130
21. A machine of the class described comprising, in combination, a bundle support; a rotary bundle-binding mechanism; means rotating the bundle-binding mechanism through more than one revolution in each cycle to encompass a bundle with wire and to provide longitudinally overlapping wire strands in a vertical plane for formation of a flat wire tie; said means consisting solely of members fixed against lateral shifting movement, and adapted to reverse the direction of the binding mechanism for each cycle of operation; and wire tying mechanism. 70 135
22. A machine of the class described comprising, in combination, a bundle support; rotary bundle-binding mechanism operating to bind a supported bundle with wire; means rotating said mechanism through more than one revolution alternately in opposite directions to encompass a bundle with wire and to provide overlapping 75 140
- means operable in a vertical plane at right angles 80 145
- 150

strands in a vertical plane for formation of a flat tie; said rotating means comprising a train of inter-connected rotative elements, and a toothed element fixed against lateral shifting movement 5 and operable alternately in opposite directions in engagement with one of said rotative elements for reversing the direction of movement of the mechanism, through said rotative elements, for each cycle of operation; and wire tying mechanism to unite said overlapped strands into the flat tie at the completion of each direction of movement of the binding mechanism.

23. A machine of the class described comprising, in combination, a frame; a fixed horizontal roller conveyer on the frame providing a bundle support; rotary bundle binding means; power-actuated bundle clamping means movable vertically relative to the support to hold the bundle on the roller conveyer; and resilient means for 15 releasing the clamp from the bundle when the bundle is bound and tied.

24. A machine of the class described comprising, in combination, a bundle support; and bundle clamping means comprising a cylinder, a piston in the cylinder, a rod connected to the piston and extending above the bundle support, a bundle clamping arm adjustably mounted on the rod, a compressible spring interposed between the piston and a cylinder end and normally holding 25 the arm spaced above the support, and means for conducting fluid under pressure into the cylinder to effect bundle clamping.

25. A machine of the class described comprising, in combination, an annular rotary bundle-binding member; rotary wire-guiding means over 30 which a wire passes and rotary wire-leading means between which the wire passes carried upon the annular member; a bundle support surrounded by the annular member; means for 35 clamping a bundle on the support; means for effecting simultaneous actuation of the clamping means and the bundle-binding member; means for maintaining tension on the wire during bundle binding; a wire tying means constrained 40 with respect to said support in which the wire is directly passed twice in one direction by the wire-leading means during the binding movement of the annular member and thereby overlapped; and means for rotating said tying means to intertwist 45 the two portions into a flat tie directly said annular member completes its binding movement.

26. A machine of the class described comprising, in combination, a frame; rotary annular bundle-binding means; a bundle support; co-operating wire-guiding means carried upon the frame and upon the bundle binding means; means consisting solely of members fixed against lateral shifting movement for rotating the bundle-binding means to effect the binding of 55 the bundle; means for maintaining tension on the wire; wire tying mechanism comprising a wire twister for forming a flat tie in which the wire is directly passed twice in one direction and overlapped during rotation of the bundle-binding means; and means mounted on one of said members of the means for rotating said binding means operable to render the tying mechanism active to 60 form the flat tie directly said binding means completes its binding movement.

27. A machine of the class described comprising, in combination, a frame; a rotary bundle-binding member; a bundle support provided upon the frame; wire guiding means carried upon the frame and upon the binding member; means for 65 maintaining tension on the wire; means for ro-

tating the binding means in reverse directions; and wire tying mechanism fixed relative to the frame and actuated at the end of each cycle of movement of the binding means.

28. A machine of the class described comprising, in combination, rotary bundle-binding means; means to reverse direction of rotation thereof for each cycle of movement; said reversing means consisting of a train of interconnected rotative elements, and a toothed element fixed 80 against lateral shifting movement engaging one of said rotative elements for reversing the binding direction of movement of the bundle-binding means through said rotative elements for each cycle of operation; wire tying means; and wire gripping means at opposite sides of the wire tying means; said parts operating to bind the bundle with the wire, then to form the tie, and to release the tie at either side of the wire tying means.

29. A machine of the class described comprising, in combination, a rotary reversible bundle-binding member; wire tying mechanism; wire-end gripping means in duplicate arranged near the tying mechanism and operable alternately to 100 grip the wire before each binding operation; means for rotating and reversing the bundle-binding member consisting solely of members fixed against lateral shifting movement; and means on one of said members of the rotating and 105 reversing means for rendering the tying mechanism and the gripping means active in timed relation with the bundle-binding member.

30. A machine of the class described comprising, in combination, a bundle support; a rotary annular bundle-binding member surrounding the bundle support; means for clamping a bundle on the support; means for simultaneously rotating the bundle-binding member to effect the binding of a bundle and to actuate the clamping means, a 110 series of spaced wire guiding wheels carried upon the annular member, two of said wheels close together to permit the wire to lead off from either during bundle binding; and a wire end gripper 115 fixed relative to the support.

31. A machine of the class described comprising, in combination, a bundle support; a bundle-positioning abutment; means for holding one end of a wire adjacent the abutment-positioned face of the bundle intermediate the longitudinal edges 120 of said face; tying means for forming a flat tie mounted on said abutment adjacent the holding means; a rotary bundle-binding member movable completely around the bundle for laying a wire 125 successively in contact with three faces of the bundle and overlapping the wire within the tying means in the cycle of operation of the member; and means for reversing the binding member relative to the holding means for each binding operation comprising a reversing gear, connections interposed between said gear and the binding member, and a toothed element fixed against lateral shifting movement and operable alternately in opposite directions in mesh with said reversing gear.

32. A machine of the class described comprising, in combination, a machine frame providing a bundle support; a rotary annular bundle-binding member surrounding said support; wire guiding and wire leading wheels rotatable on said member; wire guiding means carried by the machine frame; and wire tying means; means for clamping a bundle on the support; and means for simultaneously rotating the bundle-binding member and to actuate the clamping means; the 130

- lead-off wheels on said annular binding member binding the wire about the bundle and the guiding wheels thereon holding the wire spaced from the bundle while the wire is encircled about the 5 bundle and laid into the wire tying means.
33. A machine of the class described comprising, in combination, a bundle support; a plurality of spaced wire end gripping means adjacent one side of the support; rotatable bundle-binding means surrounding the support; means for clamping a bundle on the support; means for simultaneously rotating the binding means and actuating the clamping means; to place a wire about the sides of the bundle successively, to lie 10 in contact with said sides and to deliver the wire into position for gripping by each of said gripping means; and wire tensioning means maintaining tension on the wire in all positions of the binding means.
34. A machine of the class described comprising, in combination, an annular binding member having wire guiding means spaced therearound and constructed and arranged to lay a wire around a bundle upon actuation of 15 the member; spaced wire retaining means movable into operative position in the path of movement of the wire; wire tying means including a rotary slotted twister between said spaced means encircled by said member and constructed and 20 arranged to receive tie strands of the wire from said member in overlapping relation; driving means for the annular member consisting solely of members fixed against lateral shifting movement; means mounted on one of said members 25 for causing rotation of said twister to form a flat tie with said strands; and means for effecting retraction of the retaining means to release the tie sidewise toward the bundle.
35. A machine of the class described, comprising, in combination, means for securing the end 0 of a strand of wire; rotary reversible bundle-binding means including two wire guides between which a wire passes; means for rotating the binding means through more than one revolution whereby the wire is wrapped into band 5 formation about the bundle, said wire being disengaged from one guide and contacted by the other for effecting tight hugging of the wire against three sides of the bundle during its binding cycle to encompass a bundle with the wire 10 and to provide overlapping strands of the wire beyond the secured end for the forming of a flat tie; said means consisting solely of members fixed against lateral shifting movement; means operable directly the binding means completes its 15 cycle of binding movement to unite the overlapped portions of the strands into the flat tie; and a plurality of wire tensioning means operable to maintain a substantially constant tension 20 on the wire in all positions of said binding means.
36. A machine of the class described comprising, in combination, a frame; a bundle support, means for clamping a bundle on the support; rotary bundle-binding means including two wire guides disposed at each side of a strand of wire 25 for flexing and wrapping the wire into band formation about a bundle and tightly against three sides thereof, wire tying means for forming a flat tie; means for actuating the clamp; means for simultaneously rotating the bundle-binding means and actuating the clamping means; and wire tensioning means carried by the machine frame at one side of the rotary bundle-binding means and means automatically operable to maintain tension on the wire.
37. A machine of the class described comprising, in combination, an annular bundle-binding member; means for actuating said annular member consisting solely of members fixed against lateral shifting movement; spaced wheels and 30 coadjacent wire lead-off wheels on said member; wire tying mechanism for forming a flat tie including a rotary slotted twister and spring-actuated wire retaining elements spaced from and at each side of the twister; said guiding wheels holding the wire spaced from all parts of the bundle while the lead wire is encircled into band formation about the bundle and laid in contact with said retaining elements and in the slot of the twister by the lead-off wheels.
38. A machine of the class described comprising, in combination, a rotary annular bundle-binding member; means for actuating said annular member consisting solely of members fixed against lateral shifting movement; wire lead off 35 and wire guiding means on said annular member for guiding and supporting the wire; and mechanism for forming a flat tie including a rotary slotted twister; spring-actuated wire retaining elements spaced from and at each side 40 of the twister; and wire end grippers mounted near the retaining elements; two of said guiding means binding the wire about a bundle and the other of said guiding and supporting means holding the wire spaced from all parts of the bundle while the lead of the wire is encircled into band formation about the bundle and has been carried into contact with the retaining elements and into the slotted twister.
39. A machine of the class described comprising, in combination, an annular rotary bundle-binding member; spaced wire-guiding wheels carried on one side of said member; two of said wheels having their peripheries close together so that the wire leads off from either, or both, 45 for effecting the binding of the bundle; and means to rotate said member consisting solely of members fixed against lateral shifting movement.
40. A machine of the class described comprising, in combination, an annular wire-guiding member carrying spaced wire-guiding wheels on one side thereof, two of said wheels having their peripheries close together so that the wire leads off from either, or both, during binding of the 50 bundle; and means to rotate said member comprising a reversing gear, rotatably mounted gearing interposed between said gear and said member, and a toothed element fixed against lateral shifting movement operable alternately 55 in opposite directions in mesh with said reversing gear for rotating said member through more than one complete revolution alternately in opposite directions.
41. A machine of the class described comprising, in combination, a bundle support; bundle-binding means; mechanism for forming a flat tie surrounded by the bundle-binding means; said mechanism including a rotary slotted twister, spring-projected wire retaining means spaced 60 from and at each side of said twister, and wire end grippers mounted near the retaining means; a bundle positioning abutment to permit placing the bundle close to the tying means and having a passageway for the wire; means for actuating 65 the bundle-binding means consisting solely of members fixed against lateral shifting movement; and means mounted on one of said members for causing actuation of the twister, the retaining means, and the grippers in timed relation with 70

- the bundle-binding means; the parts being constructed and arranged to provide overlapping of the wire in a vertical plane within the tying means and to discharge the tied wire through said 5 passageway.
42. A machine of the class described comprising, in combination, a bundle support; rotary annular wire-guiding means constructed and arranged to lay a wire around a bundle in opposite 10 directions; means for rotating said annular wire guiding means in said opposite directions comprising a rack and pinion reversing the direction of rotation thereof with an interval of rest between said directions of movement; mechanism 15 operable during said interval of rest for forming a flat tie with portions of the wire laid about the bundle; and automatically acting means to maintain a substantially uniform tension on the wire irrespective of its movement.
43. A machine of the class described comprising, in combination, a bundle support; fluid-actuated means for clamping a bundle on the support; means for convexing a wire and binding a bundle with the convexed wire so as to provide 20 a band thereabout pressing inwardly against three sides of the bundle, with paralleling strands thereof overlapped in tying location adjacent the fourth side thereof; and means for twisting said overlapped strands to form a tie reacting during 25 the major portion of its formation against the resistance of the bundle only.
44. A machine of the class described comprising, in combination, a rotary bundle-binding member constructed and arranged to envelop 30 completely a supported bundle with a wire with portions of the wire overlapping; a wire tying mechanism including a wire twisting member having a longitudinal slot; the parts being so constructed and arranged that the wire is laid in 35 said slot after the rotary bundle-binding member starts to rotate and is again laid in said slot after envelopment of the bundle; means for rotating the bundle-binding member consisting solely of members fixed against lateral shifting 40 movement; and means for rotating the twisting member to intertwist said portions of the wire into a flat tie and to position said slot toward the bundle for discharge of the tie; the rotation 45 of the twister beginning directly the binding member completes the envelopment of the bundle.
45. A machine of the class described comprising, in combination, mechanism surrounding the object to be bound for guiding and laying a band 50 completely around said object during each cycle of movement in one direction; means activated independently of any contact with the bundle for actuating said mechanism alternately in opposite directions to effect binding of the objects alternately in opposite directions; said activated means consisting solely of members fixed against lateral shifting movement; and means for maintaining the wire taut during movement of the bundle-binding mechanism in said opposite directions.
46. A machine of the class described comprising, in combination, a bundle support; an annular bundle-binding member surrounding the bundle support; driving means for said member 55 activated independently of any contact with the bundle for rotating said member alternately in opposite directions to effect binding of the bundles alternately in opposite directions; said activated means comprising a reversing gear, driving 60 connections interposed between said reversing gear and the annular bundle-binding member, and a toothed driving element operable alternately in opposite directions in mesh with said reversing gear.
47. A machine of the class described comprising, in combination, an annular bundle-binding member; a slotted rotary twister; the bundle binding member being constructed and arranged to place a wire completely around a bundle to overlap the wire within the slot of the twister; and means activated independently of any contact with the bundle for rotating the bundle-binding member in opposite directions with an interval of rest; said activated means comprising a reversing gear, driving connections interposed between said reversing gear and the annular bundle-binding member, and a toothed driving element operable in opposite directions in mesh with said reversing gear; and means operable during the interval of rest to rotate the twister to unite the overlapped wire into a flat tie.
48. A machine of the class described comprising, in combination, mechanism for guiding and laying a wire band completely about a bundle in one cycle of movement; means for tying the band so laid; and driving means activated independently of any contact with the bundle for effecting reversal of the band-guiding and laying mechanism to enclose a second bundle with a band in the opposite cycle of movement; said driving means comprising a rack and pinion operable to reverse the direction of rotation of the mechanism for each cycle of movement.
49. A machine of the class described comprising, in combination, spaced bundle supporting elements; a slotted rotary twister; an annular bundle-binding member movable in a vertical plane intermediate said elements; the bundle binding member being constructed and arranged to place a wire completely around a bundle placed in binding position on said supports and to overlap the wire within the slot of the twister; means activated independently of any contact with the bundle for rotating the bundle-binding member in opposite directions with an interval of rest; said activated means consisting of a train of interconnected rotative elements fixed against lateral shifting movement, and a reciprocable toothed element engaging one of said rotative elements for reversing the direction of movement of the annular bundle-binding member for each binding operation; and means operable during the interval of rest to rotate the twister to unite the overlapped wire into a flat tie.
50. A machine of the class described comprising, in combination, spaced bundle supporting elements; spaced bundle registering elements; fluid actuated means for clamping a bundle in binding position on the supporting elements; means for holding the end of a wire; a slotted rotary twister; an annular bundle-binding member movable in clockwise and counterclockwise directions in a vertical plane intermediate said spaced bundle supports; the binding member being constructed and arranged to place a wire completely around a bundle positioned and registered on said supports and to overlap the wire within the slot of the twister; means activated independently of any contact with the bundle for rotating the bundle-binding member in opposite directions; said activated means comprising a rotatable shaft, a train of rotatably mounted gearing having one of its elements engaged with the annular bundle-binding member and

- another of its elements secured to said shaft, a pinion gear secured to said shaft, a toothed element fixed against lateral shifting movement operable in opposite directions in mesh with said 5 pinion gear for imparting clockwise and counter-clockwise directions of movement to the member through said gearing; means for rotating the twister to form a flat tie; and resilient means for effecting release of the clamping means from 10 the tied bundle. 51. A machine of the class described comprising, in combination, a frame; means for holding the lead of a wire adjacent the end thereof; means on the frame active on the strand of wire for effecting predetermined tensioning and controlled delivery thereof; means on the frame intermediate the holding means and the tensioning means for effecting adjustable retraction and tensioning of a portion of the wire delivered under predetermined tension; and wire guiding means associated with the first mentioned tensioning and controlling means adapted to effect removal of kinks and twists from the wire prior to the tensioning and controlled delivery thereof. 52. A machine of the class described comprising, in combination, a frame; means on the frame active on a strand of wire for effecting predetermined tensioning and controlled delivery thereof; means on the frame for effecting adjustable 15 retraction and tensioning of a portion of the delivered wire; and means associated with the first mentioned means adapted to effect removal of kinks and twists from a supply of said strand prior to the tensioning thereof. 53. A machine of the class described comprising, in combination, a frame; a device on the frame including a plurality of grooved rollers constructed and arranged in staggered relation in a vertical plane for effecting tensioning and 20 controlled delivery of a strand of wire; means on the frame constructed and arranged in the path of said delivered wire for actively retracting and adjustably tensioning a portion of said delivered wire; and a device having an elongated 25 bore for removing kinks from and guiding a supply portion of the wire into alignment with the grooves of said staggered rollers. 54. A machine of the class described comprising, in combination, a frame; a device on the frame including a plurality of grooved rollers constructed and arranged in staggered relation in a vertical plane for effecting tensioning and controlled delivery of a strand of wire; means on the frame constructed and arranged in the path 30 of the wire delivered by said device for actively retracting and adjustably tensioning said wire; means associated with said means for cushioning the action thereof; bundle-binding means operable in clockwise and counterclockwise directions in a vertical plane to provide overlapping portions of the strand in said plane, for the formation of a tie, during each direction of movement of said bundle-binding means; wire tying mechanism; and means on the frame for guiding the tensioned wire into the plane of movement of the bundle-binding means. 55. A machine of the class described comprising, in combination, a frame; a device on the frame including a plurality of grooved rollers 35 constructed and arranged in staggered relation in a vertical plane for effecting tensioning and controlled delivery of a strand of wire; means on the frame, constructed and arranged in the path of the wire delivered by said device, for actively retracting and adjustably tensioning 40 said delivered wire; means associated with said means for cushioning the action thereof; a slotted rotary twister; bundle-binding means having a path of travel in register with the slot of said twister; means on the frame for guiding the tensioned wire into the path of movement of the bundle-binding means; means for actuating said bundle-binding means for more than one revolution to encompass a bundle with a wire and to provide dual overlapping tie portions of the wire within the slot of the twister; and means for actuating said twister to unite said overlapped strands. 56. In a bundle tying machine, a frame adapted to hold the bundle to be tied, a slotted wire twisting device arranged contiguous to the side of the held bundle, the slot in the twisting device being parallel to the contiguous side of the bundle whereby the twisted wire will lie parallel to the contiguous side, means for passing a wire around the bundle and twice in the same direction through said slot, whereby the portions of the wire disposed in the slot are overlapped, means for actuating the passing means consisting solely of members fixed against lateral shifting movement; and means on one of said actuating members for causing rotation of the twisting device to twist the overlapping portions of the wire together. 57. In a tying machine, means for gripping a wire; means for effecting flexing and encircling of the wire in a vertical plane tightly against three sides of an object as it is passed more than completely around the object to provide overlapping portions of the encircled wire beyond the gripper in said plane; a wire tying means positioned in the path of movement of the wire for receiving and intertwisting said overlapping portions of the banded wire to form a flat joint; and means for actuating the aforementioned means in timed relation whereby the intertwisting means is operative directly upon completion of the binding movement of the convexing and encircling means. 58. In a tying machine, means for gripping a wire; means for effecting flexing and encircling of the wire in a vertical plane tightly against three sides of an object as it is passed more than completely around the object to provide overlapping portions of the encircled wire beyond the gripper in said plane; means adjustably operative on the wire for maintaining the wire under tension during the movement of the encircling means; a wire tying means positioned in the path of movement of the wire for receiving and intertwisting said overlapping portions of the banded wire to form a flat joint, and means for actuating the aforementioned means in timed relation whereby the intertwisting means is operative directly upon completion of the binding movement of the convexing and encircling means. 59. In a tying machine, means for effecting encircling of a tensioned binding strip about an object to be bound and tied, said means including a rotating member; spaced means for maintaining portions of the strip spaced from the object; a wire tying means positioned in the path of movement of the wire intermediate the spaced means for receiving and securing said portions of the strip in a substantially flat joint; and means for rotating the bundle-binding member consisting solely of members fixed against lateral shifting movement, one of said members having means mounted thereon for rendering the securing means active directly the rotating member completes the binding of the bundle and for re- 100 105 110 115 120 125 130 135 140 145 150

tracting the maintaining means to release the flat joint.

60. In a binding machine, in combination, an annular member adapted to surround an object and rotatable about the object in a given plane for more than the perimeter thereof to provide longitudinally disposed passing portions of the encircled strip in said plane; means for uniting said passing portions in a substantially flat joint; and means for actuating the annular member consisting solely of members fixed against lateral shifting movement.

61. In a binding machine, in combination, a rotatable annular member mounted for movement in a curvilinear path around an object to be bound and tied; means for supplying a binding strip to said member; means for maintaining the binding strip under tension; means spaced from the supply means for gripping the lead of the strip; means for rotating the member to effect encircling of the strip extending from the gripping means about the object in a given plane for more than the perimeter of the object to provide one portion of the strip longitudinally overlapping another portion of the strip in said plane; means for uniting said overlapping portions in a substantially flat joint; and means for actuating the bundle-binding member and the uniting means in timed relation, said actuating means consisting solely of members fixed against lateral shifting movement.

62. In a wire tying machine, a rotatable ring, means for supplying wire to said ring, said ring having a wire lead-off member movable orbitally about an object to be tied upon rotation of the ring, means for rotating the ring to effect encircling of the wire in a given plane about the object, means for intertwisting adjacent portions of the wire into a flat knot; said latter means comprising a rotary slotted twister having its slot in register in the plane of movement of the wire for receiving said adjacent portions of the encircled wire directly from the lead-off member during rotation of the ring; and means for effecting rotation of the ring and the intertwisting means in timed relation whereby the twister begins its operation directly the ring completes its movement of encircling the wire about the object.

63. In a bundle tying machine, a wire gripper comprising a head and a projection thereon, an adjustable gripper element, means for operating the gripper to clamp the wire against said adjustable gripper element, means for passing the wire around the bundle in a direction to bend it around and against said projection, and means for holding the wire in tension.

64. In a wire tying machine a clamping element, an adjustable wire gripper movable relative to said element and comprising a head and a projection thereon, means for operating the gripper to hold the wire between the projection and the element, and means for passing the held wire around an object in a direction to bend it around and in contact with said projection.

65. In a wire tying machine, a rotatable ring for effecting winding of wire about an object to be bound and tied, means for mounting the ring to allow rotation in reverse directions, means for securing the wire in a flat tie for each direction of rotation of the ring; means for rotating and reversing the ring consisting solely of members fixed against lateral shifting movement; said means effecting starting, reversing, stopping and holding of the ring for each cycle of operation of

the machine; and means for maintaining the wire taut when the direction of rotation of the ring is reversed.

66. In a wire tying machine, a wire gripper, an adjustable gripper element, means for operating the gripper to clamp the wire against said adjustable gripper element, a rotatable ring for effecting winding of the wire about an object to be bound and tied, means for mounting the ring to allow rotation in reverse directions, means for guiding wire along the periphery of said ring, and means for maintaining the wire taut when the direction of rotation of the ring is reversed.

67. In a wire tying machine, a rotatable ring, a slotted twister within the ring for forming a flat knot from overlapped portions of wire, means for supplying wire to said ring, and means for rotating the ring comprising a rack and pinion reversing the direction of rotation of the ring relative to the twister to effect encircling of the wire about an object to be bound and tied and to directly pass and overlap portions of said wire in the slot of the twister.

68. In a wire tying machine, a rotatable ring, a slotted twister positioned within the ring and substantially in the plane of the ring for forming a flat knot from overlapped portions of wire, means for supplying wire to said ring, and means for rotating the ring comprising a reversing gear, gearing interposed between the reversing gear and the ring, and a toothed element fixed against lateral shifting movement operable in opposite directions for reversing the direction of rotation of the ring, through said gearing, relative to the twister to effect encircling of the wire about an object to be bound and tied and to directly pass and overlap portions of the wire in the slot of said twister.

69. In a wire tying machine, a rotatable ring, a slotted twister, positioned within the ring and substantially in the plane of the ring for forming a flat knot from overlapped portions of wire, said twister being also mounted in an upright position whereby the overlapped portions will lie in a substantially vertical plane, means for supplying wire to said ring, and means for rotating the ring comprising a rack and pinion reversing the direction of rotation of the ring relative to the twister to effect encircling of the wire about an object to be bound and tied and to overlap portions of the wire in the slot of the twister.

70. In a tying machine, means including a rotatable ring for effecting encircling of a binding wire about an object to be bound and tied; a rotatable twister within said ring and having a slot opening toward the periphery of the ring to receive overlapped portions of the wire, means for rotating the twister to intertwist said portions and to position said slot toward the center of the ring for discharge of the twisted portions; and power operated means for reversing and actuating the ring in opposite directions relative to the twister comprising a rotatable shaft, a reversing gear secured to said shaft, another gear secured to said shaft, gearing connections interposed between the last named gear and the ring, a toothed element fixed against lateral shifting movement and movable in opposite directions in mesh with said reversing gear, and a reciprocable driving element connected with said toothed element.

71. In a binding machine, means for gripping a binding wire, means for forming a flat tie including a rotary slotted twister, means for tensioning the wire, means including a rotatable ring for effecting encircling of the gripped and

tensioned wire about an object to be bound, said wire entering the slot of the twister then enveloping the successive faces of the object and again entering the slot of the twister to overlie the initially positioned wire through actuation of said ring, means on the ring for holding the wire adjacent the periphery thereof, said latter means including a wire lead-off member intermediate the gripping and the tensioning means for effecting tight hugging of the wire against the object; and means for actuating the ring consisting solely of members fixed against lateral shifting 80 movement.
